Attorney

UNITED STATES PATENT OFFICE.

MARY J. DENISON, OF JOHNSVILLE, OHIO.

CULINARY ARTICLE.

SPECIFICATION forming part of Letters Patent No. 472,527, dated April 12, 1892.

Application filed October 29, 1891. Serial No. 410,277. (No model.)

To all whom it may concern:

Be it known that I, MARY J. DENISON, a citizen of the United States, residing at Johnsville, in the county of Morrow, State of Ohio, 5 have invented certain new and useful Improvements in Culinary Articles, of which the following is a specification, reference being had therein to the accompanying drawings.

10 This invention relates to certain new and useful improvements in culinary articles; and it has for its objects, among others, to provide an improved, cheap, and simple oven for use in connection with gas or gasoline 15 stoves, so constructed as to economize space and heat and also provide for the cooking of a variety of different articles of food at one and the same time.

15 I provide a suitable receptacle without bottom, and within this receptacle provide supports for separate independent removable false bottoms, whereby the inner receptacles may be held independently of each other, and any one or more may be placed directly 20 upon the said supports or have a false bottom between the same and the stove. The false bottoms are preferably provided with upwardly-extending flanges, which serve to 25 separate the inner receptacles, and also serve 30 as means for the better handling of the bottoms.

Other objects and advantages of the invention will hereinafter appear, and the novel features thereof will be specifically defined 35 by the appended claims.

The invention is clearly illustrated in the accompanying drawings, which, with the letters of reference marked thereon, form a part of this specification, and in which—

40 Figure 1 is a central vertical section through my improved oven. Fig. 2 is a perspective of the lower portion, with parts broken away. Fig. 3 is a plan with the inner removable receptacles removed.

45 Like letters of reference indicate like parts throughout the several views in which they occur.

Referring now to the details of the drawings by letter, A designates a preferably rectangular outer case, which may be of any 50 suitable size and material, and provided with

suitable handles a. It may be beaded around the lower edge, as seen at a', to strengthen the same, and is provided with a suitable cover or lid B, as seen in Fig. 1. This case 55 is without bottom; but around the inner lower edge there are supports for a false bottom or for the bottoms of the inner receptacles. As herein shown, these supports are provided by means of angle-bars around the edges, 60 with their vertical sides secured to the vertical inner sides of the outer case and their horizontal sides extending inward for a sufficient distance to form a sufficiently wide and strong support. Supported upon these bars 65 are the intersecting or crossed T-bars D, which are of sufficient length to have their ends rest upon the supports C, as shown best in Fig. 2.

70 E are separate independent receptacles for food or the like. In the form shown there are provisions for the support of four of such receptacles; but the number may be varied without departing from the essence of the invention. In practice these receptacles may 75 be supported directly upon the supports thus formed, or they may be supported upon false bottoms F, designed to be supported upon the said supports. One or more receptacles may be supported upon the false bottoms 80 and the others directly upon the said supports, according to the degree of heat required. The false bottoms may be provided with a flange d upon one or more sides to 85 separate the receptacles, and these flanges may be provided with perforations f, as seen in Fig. 2, to permit of the better circulation of the heated air.

The advantages of the invention are apparent and its manner of use obvious. 90

I am aware that it is not new to provide cooking apparatus with means for supporting a plurality of vessels, one above the other, and do not seek to cover such construction. I deem it important that the supports be so 95 arranged as to support a plurality of vessels in the same horizontal plane, whereby they may all be subjected to practically the same degree of heat, so that a plurality of articles of food may be cooked, all at the same time 100 and all be done at the same time, ready to serve.

What I claim as new is—

1. An oven consisting of a bottomless outer case with interior supports and removable false bottoms having upwardly-extended per-
5 forated flanges in the same horizontal plane, as set forth.

2. An oven consisting of an outer bottom-
less case, angle-bars secured to the inner
walls thereof at the lower edge, T-bars sup-
6 ported thereon, and removable independent

false bottoms supported upon the said bars, all in the same horizontal plane, substantially as specified.

In testimony whereof I affix my signature in presence of two witnesses.

MARY J. DENISON.

Witnesses:

J. C. LASER,
HATTIE AULD.
